UNITED STATES PATENT OFFICE

JOHN C. MERTENS, OF CHICAGO, ILLINOIS, ASSIGNOR OF ONE-HALF TO
JOSEPH HANREDDY, OF CHICAGO, ILLINOIS.

ASPHALT-CUTTING MECHANISM.

No. 832,919.

Specification of Letters Patent.

Patented Oct. 9, 1906.

Application filed April 21, 1906. Serial No. 313,013.

To all whom it may concern:

Be it known that I, JOHN C. MERTENS, a citizen of the United States, residing at Chicago, county of Cook, and State of Illinois, have invented certain new and useful Improvements in Asphalt-Cutting Mechanism, of which the following is a specification.

This device is particularly intended for use in cutting out asphalt or similar substances from freight-cars in which it is shipped in bulk, although the device might be used for cutting substances out of other receptacles or vehicles from which it is difficult to cut out the asphalt by means of picks, spades, or similar hand implements.

In the shipping of asphalt the substance, which is of a more or less viscous nature, becomes solidly packed or caked in the car, so that when it is time to remove the same the asphalt will have assumed the form of a hard compact cake, filling the car from end to end, and in this condition it is a very difficult and laborious operation to pry or dig it out of the car by the use of ordinary implements.

The object of the present invention is to provide a cutter for use in removing asphalt which can be easily shifted from car to car and can be moved to any position upon a car, thereby enabling all of the asphalt or similar substance to be cut out without difficulty and in a much more rapid, economical, and satisfactory manner than has hitherto been the case.

Other objects of the invention are to improve the construction and arrangement of the trackways along which the cutting mechanism is moved and to improve the construction and arrangement of the device as a whole and of the individual parts thereof.

The invention consists in the features of construction and combination of parts hereinafter described and claimed.

In the drawings, Figure 1 is a side elevation of the cutting mechanism mounted upon a freight-car having a metallic body, the car being shown in section. Fig. 2 is a longitudinal sectional view of the screw and gear mechanism; Fig. 3, an edge view of the cutting-spade; and Fig. 4, a cross-sectional view of the gear-wheel hub and screw-stem, showing the spline or key connecting the two.

The cutting mechanism consists of a spade 1, having side plates 2 at substantially right angles to each other, which side plates con-

verge to a point 3, giving the entire spade a wedge-shaped formation. The side plates are sharpened to provide cutting edges 4, and at the inner angle of the two side cutting-plates is a bulb or socket 5, which fills the corner and is upwardly tapered from a point 6 to an upwardly-projecting socket 7 of sufficient size to receive and hold the end of a feed-screw 8. By reason of the taper indicated the bulb or socket will tend to force back the asphalt cut by the knife-edges in the form of a wedge-shaped block, as shown in Fig. 1. The feed-screw is rotatably mounted and held within the socket 7 by means of a pin 9, which enters a rounded groove 10 in the end of the feed-screw, which permits the feed-screw to revolve and prevents the withdrawal of the feed-screw from the spade and feeds without revolving it. The feed-screw terminates at its upper end in a stem or shank 11, and the screw and shank are provided with a longitudinally-extending groove 12.

The stem is slidably mounted within the hub 13 of a bevel-faced gear-wheel 14 and is compelled to revolve therewith by reason of a spline or key 15, which enters the groove and compels the rotation of the feed-screw with the gear-wheel, but permits the feed-screw to slide up and down during rotation. The feed-screw is mounted within a bearing-block 16, preferably of hardened steel, which block is mounted within a slidable cast-iron body-block 17, provided at its upper end with a circular neck or flange 18. The hub 13 is journaled within a socket or cup 19 and rests upon a suitable bearing-washer 20, and the hub is further provided with a shoulder 21, which affords additional bearing-surface for the rotation of the gear-wheel. The socket 19 is provided with a flange 22, which is bolted or otherwise secured to an elongated plate 23, which latter is supported upon I-beams 24, which are of sufficient length to extend transversely from side to side of the car and are spaced from one another a suitable width to support the body-block 17 and permit it to be moved or slid along between the I-beams to change the position of the cutting mechanism, as desired. The elongated plate 23 is adapted to be clamped to the upper flanges of the I-beams by means of clamps 25, which are capable of being tightened by means of nuts 26, clamping the plate

and the mechanism supported thereby firmly to the I-beams. The plate is supported above the I-beams by means of rails or bars 27, which furnish a bearing-surface for the 5 movement of the mechanism.

In suitable proximity to the gear-wheel are a pair of uprights or standards 28, which are bolted or otherwise rigidly secured to the elongated supporting-plate 23, and between 10 the standards is a cross-bar 29, which bridges the space between the standards and has secured thereto on its under face a journal-box 30, which supports the end of a power-shaft 31, which has mounted thereon a beveled 15 pinion 32, meshing with the bevel-faced gear-wheel 14. Rotation is imparted to the power-shaft by means of a motor 33, which is likewise bolted to the elongated supporting-plate, and intermediate the pinion and 20 the motor is a clutch 34, of any suitable character, adapted to be actuated by means of a lever 35, all of which are supported upon and movable with the supporting-plate.

The ends of the I-beams are clamped to 25 flanges 36 on the car-body 37 by means of clamps 38, which are adapted to be tightened by means of nuts 39, screw-threaded onto a clamping bolt or rod 40. This arrangement permits the mechanism to be supported in 30 any suitable position on the car.

In operation the I-beams are clamped to a car containing asphalt in bulk in suitable position to begin the work, and the feed mechanism and spade are then moved to 35 proper transverse position with respect to the car. The motor is then set in motion, and when it is desirable to begin the digging operation the clutch is thrown into position to transmit power to the gear-wheel, which in 40 revolving feeds the spade forward and forces it down into the asphalt, causing the cutting or knife edges of the spade to cut out a wedge-shaped block of asphalt from the mass contained in the car. In loading the 45 asphalt it is customary to provide an open space for the initial operation of the spade by placing a bulkhead across one corner of the car, and after a start has been made within the space provided for forcing back the severed block, as shown in Fig. 1, the cutting 50 operation may proceed with great rapidity. The tapered bulb squeezes the severed block or wedge of asphalt back and away from the mass as it is severed therefrom by the knife, 55 and this operation will continue until a complete block or wedge of asphalt has been cut from top to bottom of the mass, after which the spade can be raised by reversing the feed of the screw, for which purpose a motor or engine adapted to be reversed should be employed. This motor may be a steam-engine 60 or electric motor or a motor of any style adapted to feed the screw in either direction. After the first cut has been made with the 65 spade the cutting mechanism can be shifted

slightly along the I-beams, which form guide-rails, and a second cut can then be made, and the work will continue in the same manner until the cutting mechanism has been moved back as far as it will be possible to move it 70 along the I-beams, the limit of movement being reached when the motor is brought into line with the side of the car. When the limit of movement has been reached in one direction, the entire mechanism carried by 75 the elongated supporting-plate 23 will be swung around the neck 18 of the body-block into the position indicated in dotted lines in Fig. 1, after which the work can be continued until all of the asphalt has been cut from the 80 car. In swinging the mechanism around the supporting-plate will bear against the rounded wall of the neck, and the flat bottom of the socket 19 will bear against the flat top rim or edge of the neck, and the shank of the feed- 85 screw will lend additional support during the turning operation, which arrangement provides a rigid pivotal mounting and prevents the unsupported end of the mechanism from sagging or dropping, which would be the case 90 if an insufficient pivotal mounting were provided. By constructing the mechanism in this manner it is possible to move the cutting-spade into any desired position of adjustment, and the guide-rails or I-beams need not 95 be of any greater length than the width of the car, which of course renders the operation of moving and securing the I-beams in place much simpler and easier than would be the case if it were necessary to provide rails or 100 guides of sufficient length to accommodate a cutting mechanism which could not be shifted as indicated.

It will be seen that the mechanism is not only extremely simple in construction, but is 105 also compact and adapted to be moved or shifted as an integral whole, which greatly simplifies its adjustment and use, and thereby increases its efficiency.

What I regard as new, and desire to secure 110 by Letters Patent, is—

1. In a device of the class described, the combination of guide-rails, a supporting-plate, a feed-screw around which the supporting-plate can be moved as a pivot, mechanism carried by the supporting-plate for actuating the feed-screw, and a cutter at the 115 end of the feed-screw, substantially as described.

2. In a device of the class described, the 120 combination of guide-rails, a supporting-plate, a feed-screw around which the supporting-plate can be moved as a pivot, mechanism carried by the supporting-plate for actuating the feed-screw, and a cutter at the 125 lower end of the feed-screw of wedge-shaped formation having side walls sharpened to provide knife-edges for severing a wedge-shaped block of material, substantially as described.

3. In a device of the class described, the combination of supporting guide-rails, a feed-screw, a mounting for the feed-screw adapted to be shifted with respect to the guide-rails, a supporting-plate adapted to be swung around the feed-screw as a pivot, mechanism carried by the supporting-plate for actuating the feed-screw, and a cutting implement on the lower end of the feed-screw, substantially as described.

4. In a device of the class described, the combination of supporting guide-rails, a feed-screw, a mounting for the feed-screw adapted to be shifted with respect to the guide-rails, a supporting-plate adapted to be swung around the feed-screw as a pivot, mechanism carried by the supporting-plate for actuating the feed-screw, and a wedge-shaped spade carried by the feed-screw and having diverging side plates with knife-edges and an upwardly tapering bulb-socket occupying the inner angle between the diverging side plates, substantially as described.

5. In a device of the class described, in combination with feeding mechanism, a wedge-shaped spade having diverging side walls with knife-edges and a bulb upwardly tapering from the knife-edges and occupying the inner angle between the diverging walls and terminating in a socket adapted to receive the feeding mechanism, substantially as described.

6. In a device of the class described, the combination of two **I**-beams forming guide-rails and adapted to be secured to the opposite sides of the car, a feed-screw vertically extending between the **I**-beams, a bearing for the feed-screw adapted to be shifted with respect to the **I**-beams, a supporting-plate adapted to swing around the feed-screw as a pivotal center and adapted to be clamped in adjusted position to the **I**-beams, mechanism

carried by the supporting-plate for actuating the feed-screw, and a cutter on the end of the feed-screw, substantially as described.

45

7. In a device of the class described, the combination of a pair of **I**-beams adapted to be clamped to the sides of a car, a body-block supported between the beams, a feed-screw extending vertically through the body-block and having a screw bearing therein and terminating in a smooth shank, a supporting-plate adapted to swing around the shank as an axial center, means for clamping the supporting-plate to the **I**-beams in adjusted position, a gear-wheel on the feed-screw shank fitted thereto to permit endwise movement of the feed-screw shank, a pinion for imparting rotation to the gear-wheel, a motor carried by the supporting-plate for actuating the pinion, and a cutter on the end of the feed-screw, substantially as described.

55

8. In a device of the class described, the combination of two **I**-beams adapted to be supported upon a car-body, a body-block carried between the flanges of the **I**-beams and provided with a tubular neck or collar, a feed-screw vertically extending through the body-block and terminating in a shank, a supporting-plate adapted to swing around the collar and shank as an axis, a socket surrounding the shank and secured to the supporting-plate, a gear-wheel keyed to the shank and provided with a hub journaled within the socket, a motor carried by the supporting-plate, a shaft actuated by the motor, a pinion on the shaft meshing with the gear-wheel, and a cutter on the end of the feed-screw.
